UNITED STATES PATENT OFFICE.

AUGUST CHRISTIAN NAGEL, REINHOLD HERMANN KAEMP, AND ADOLPH LINNENBRÜGGE, OF HAMBURG, GERMANY, ASSIGNEES TO NAGEL & KAEMP, OF SAME PLACE.

MACHINE FOR BREAKING OR REDUCING GRAIN.

SPECIFICATION forming part of Letters Patent No. 293,496, dated February 12, 1884.

Application filed April 23, 1883. (No model.)

To all whom it may concern:

Be it known that we, AUGUST CHRISTIAN NAGEL, REINHOLD HERMANN KAEMP, and ADOLPH LINNENBRÜGGE, all of Hamburg, German Empire, have invented new and useful Improvements in Machines for Breaking or Reducing Grain, of which the following is a specification.

This invention relates to machines in which grain is broken or reduced between disks having annular reducing-surfaces, and the improvements involve constructions of the operating-surfaces and certain other parts of the machine, so that the grain in its first passage through the machine, to release and remove impurities, will be split lengthwise while producing a minimum quantity of middlings and flour, and that in the subsequent passages of the split grain through the machine the grinding will produce middlings of high grade with but little flour.

The invention consists in disks each provided with a reducing-surface composed of inclined projections that form a diverging or funnel-like space, so that the grains shall receive but a single blow in passing between them; and in the combination therewith of throwing-ledges secured to the rotating disk; in the combination, with a stationary and a rotating disk each provided with co-operating reducing-surfaces, of throwing-ledges attached to the rotating disk but terminating a considerable distance from the said reducing-surfaces to provide a space for the free movement of the grains in their flight to the reducing-surfaces, and, in the combination with said throwing-ledges, of an auxiliary ledge for preventing the grains from falling below the path of travel thereof; in the combination, with a stationary and a moving disk each provided with reducing-surfaces and with a continuous delivery-channel receiving the reduced material from the periphery of the disks, of fans attached to the rotating disk, and running in the inner part of said channel, and operating to induce a current of air from a central feeding-channel through the said reducing-surfaces and into the delivery-channel, whereby the material is

carried and said disk is cooled; in the combination, with said disks, feeding and delivery channels, and openings communicating with the atmosphere, of fans attached to the rotating disk and running in the inner part of the delivery-channel, whereby the induced air-currents act not only to carry but to cool the material; in the combination of said disks, feeding and delivery channels, openings, and two sets of fans; and in the combination of peculiar means for regulating the distance of the reducing-surfaces from each other and the degree of pressure with which their surfaces act upon the grain.

A machine constructed according to this invention is represented on the annexed sheets of drawings, all the before-named improvements being shown combined in one machine, although it will be readily understood that certain of them may be used independently of the others, if desired.

Figure 1 of the said drawings is a longitudinal sectional elevation; Fig. 2, an end elevation, partly in section; Fig. 3, a section of a part of the machine drawn upon an enlarged scale; and Fig. 4, a section of one portion of the machine, also drawn upon an enlarged scale.

The machine constructed according to this invention is especially intended to be used in the first stage of the high-grinding or gradual-reduction process, in which it is the object, through repeated breaks or passages of the material through the machine, to produce middlings with as little flour as possible. In all the milling-machines which act with their faces against each other hitherto employed for this purpose, the co-operating faces have been made very long or arranged to be nearly parallel. Such constructions present the disadvantage of exposing the material to be reduced for too long a time to the action of the said surfaces, and consequently there is produced, together with the middlings, a considerable quantity of flour of very inferior quality. In order to reduce as much as possible this premature production of flour, we employ reducing-surfaces which are so constructed that the

ridges or projections thereof will impart to each grain or part of a grain but a single blow. These surfaces are shown in section at *c* and *C* in Figs. 1, 3, and 4, while Fig. 2 shows a part 5 of one of these surfaces in elevation.

In order to cause a splitting of the grains lengthwise, which, though of great importance, (especially with wheat, on account of the furrow in the grains,) has heretofore been attempted with but little success, the reducing-surfaces are constructed in a peculiar form and the appliances for projecting the grains outward have a special construction and arrangement in their relation to the reducing-surfaces. 10 The said surfaces are beveled or curved in such a manner that their faces shall diverge considerably in the direction toward the center of the disks, and thus to present in transverse section not only diverging breaking-surfaces, 15 but a funnel-shaped space or passage between them, as is best seen in Fig. 4. The rotating disk *b* is provided near its center with short throwing-ledges *h*, between which and the reducing-surfaces there is a comparatively large 20 space. These ledges in themselves are not new, and they serve in the first place, as in other milling-machines, to distribute the grain over the periphery of the disks. In addition thereto, however, they are constructed and arranged in this machine so that their outer ends 25 terminate a considerable distance from the reducing-surfaces, and thus provide a large space for the free movement of the grains, and hence co-operate in attaining a new result, which is 30 based on the property possessed by grains of wheat, rye, &c., to move with one of their ends foremost when falling or when flung through the air. In consequence of this construction all of the grains thrown by the ledges *h* toward the 35 reducing-surfaces will have space in which to turn and pass with their longitudinal axes nearly in a radial direction into the funnel-shaped space between the said surfaces. The 40 projections forming the reducing-spaces will then nip or seize the grains in this position and impart to them a single blow that will divide them lengthwise.

The machine represented in the drawings is provided with two vertically-arranged rotating milling-disks, *b*, and two like stationary milling-disks, *f*. The two rotating disks *b*, which may be cast together, as shown in Fig. 1, or made separate from each other, 45 are keyed on the shaft *a*, while the stationary disks *f* are supported by means of screw-rings *i* secured to them, which rings form circular bearings that fit within circular guides constituted by the walls *8* of the frame. These rings may therefore be moved in an axial direction, and they are constantly pressed toward the rotating disks by springs. The drawings show for this purpose each of the disks *f* as provided with a spiral spring, *o*, which acts 50 on the disk by means of a screw-spindle, 2, pivoted to a lever, *n*, that has a forked upper end, 6, to straddle the shaft *a* and bear upon

knobs 7, projecting from the ring *u* on opposite sides of the shaft *a*, which ring is attached to the hub of the disk *f*, that embraces said shaft. The tension of the spring is regulated 70 by a nut, 5, that runs on the screw-spindle 2, and drives a collar, 3, that bears against one end of the spring *o*, and the tension of the spring thus produced, and consequently the pressure exerted between the reducing-surfaces, may be indicated on a scale, *o'*, with which a pointer, 4, on the collar 3 registers. 75

Instead of springs, weights may be employed, which may be arranged to be regulated while the machine is in operation. The disks *f* are 80 prevented from turning by means of projections *x* cast upon them, and extended so as to embrace the opposite sides of the levers *n*. The grain or other grist to be treated is introduced through a feed-channel, *g*, into the 85 space between the disks *b* and *f*, and is there caught by the ledges *h*.

The improvements constituting this invention may also be applied to machines having but one pair of co-operating disks, and the 90 disks may be horizontal, or vertical, or inclined.

In a machine having two pairs of disks the grinding-surfaces of which are arranged horizontally, or in a position deviating considerably from the vertical, the lower pair of grinding-surfaces of the machine must be fed by special means, such as the air-current, created in the manner to be hereinafter described. When the disks are vertical, each stationary 95 disk is provided close to and below the path of the ledges *h* with a ledge, *t*, forming an arc of a circle and serving to prevent the lower part of the circumference of the disks from receiving more grist than the upper part. In 100 the practical carrying out of portions of these improvements, the reducing-surfaces may be constituted by edges, ridges, teeth, or other suitable projections, as may be required by the peculiar nature of the grist to be treated 105 or the product to be obtained; but the particular construction of these surfaces, hereinafter specifically described, constitutes an independent feature of the invention.

For controlling the quantity of grist to be 110 admitted into the machine, feed-rollers or any other known feeding device may be employed. The rotating disks *b* project beyond the outer edges of the reducing-surfaces, and upon this projecting part each of them is provided on 115 one side with fan-blades *p* and on the other side with fan-blades *p'*. These fan-blades *p* *p'* run in housings consisting of two eccentrically-shaped cases that form the channels *q* for conducting the reduced material away. These 120 housings are supported a distance apart by occasional radial ribs 16 to form openings 11, through which the air may pass from all circumferential points to the interior of the machine. The fan-blades *p* draw air through the 125 feed-channel *g* and through the space between the disks *b* and *f* and the reducing-surfaces, 130

and thus create an air-current which, in addition to its keeping the said surfaces cool, conveys the material to be acted upon to the reducing-surfaces, and the reduced grist into the channel *q* surrounding each rotating disk. The area of these channels *q* gradually increases in the direction of the air-current (see Fig. 2) and they convey the reduced material away. The fan-blades *p'* draw air through the slits *s* from the opening 11 (or in any other manner from behind the disk or disks) and drive it into the channel *q*. The current thus produced by the blades *p'* of each disk cools the latter at the back and increases the strength of the air-current in the said channels. The quantity of air drawn in by the fan-blades may be controlled by the vertical adjustment of the funnels 20 in the feed-channels *g*, and by more or less covering the opening 11, as with doors. By this ventilating arrangement an efficient cooling of the grist is also brought about; but the same has the special function of conveying the grist by means of the air-current in any required direction to the sifting or purifying machines upon which the material is to be submitted to further treatment, or to a storage-room, and of thus replacing the elevators and creepers heretofore used. For this purpose the channels *q* are connected at *r* with suitable conduits leading to the said machines or room. With these conduits suitable devices may be combined, so as to utilize the air-current in said conduits in the operation of dividing the grist, while it is being carried by the air-current, according to the specific gravity of its parts, on the well-known principle of middlings-purifiers. This ventilating means may be applied to machines of this class whether their reducing-surfaces be or be not formed as herein described.

The reducing-surfaces formed on the opposed faces of the rings *c C* are especially constructed to adapt them to the splitting of the grains, and for this purpose, whether or not their breaking-faces are more or less narrow, they are formed as inclined projections that diverge in a direction toward the center of the disks. They thus present a funnel-like passage for the material, so that the varying sizes of grain projected between them may be nipped and receive but one blow in its passage through them into the channel *q*. As the reducing-surfaces are almost the only parts of the disks subject to great wear, it is advantageous to form these surfaces on special rings *c C*, fastened in such a manner to the disks that they may be removed and exchanged.

Similar arrangements have heretofore been applied in milling-machines; but these separable parts have always been fastened by bolts or screws and other like means of difficult manipulation and destructive application.

For the purpose of avoiding the weakening of the narrow rings by bolt or screw holes, and to do away with the operations of drilling and tapping the hardened portions thereof, and to

obtain a connection which allows a speedy exchange of the rings and at the same time insures their true concentric position, the means of attachment shown in the drawings have been devised. These means consist in the rings *d* and *e*, screwed onto screw-threads cut in offsets of the disks, and with their outer edges overlapping the inner edges of the rings *c C*. A rotation of the rings on the disks is prevented by means of short studs or pins inserted into the rings and the disks, as in Fig. 3, which may readily be done, as the drilling of the holes for them into the back part of the rings presents no difficulty, as this part is soft. Each stationary disk *f* is guided in its axial adjustment and maintained at the desired distance from the co-operating rotating disk *b* by an adjusting-ring *i*, screwed on the periphery of the disk *f*. This ring and disk are pressed inward by the force of the aforesaid spring *o*, or the weight which may be used instead thereof, until the projection *v* abuts against the machine-frame, and thus limits the extent to which the reducing-surface of the disk *f* is moved forward relatively to the reducing-surface of the disk *b*. The rim *w* of the ring operates as the guide for the disk *f* in the opening of the frame, as before stated. On its periphery the ring *i* has teeth *m*, constituting a wheel, with which gears a pinion, 25, connected with the hand-wheel *k*. A rotation of the wheel *k* will consequently produce a rotative movement of the ring *i*, which, being always pressed against the frame, causes the disk *f* to be moved forward or backward and the distance between the reducing-surfaces to be varied and adjusted. This distance may be indicated on a scale, if desired. The rotation of the ring *i* may, however, also be caused by other mechanical means—as, for instance, by a lever and pawl.

The specified means of fastening the rings *c C* on the disks and of adjusting the distance of the reducing-surfaces from each other and the pressure between them may be applied to machines of this class whether their reducing-surfaces be or be not formed as hereinbefore set forth.

What, therefore, is claimed is—

1. The combination of a stationary disk and a rotating disk, each provided with a reducing-surface composed of inclined projections that form a diverging or funnel-like space between them, and adapt them to deliver but a single blow to the grains, substantially as shown and described.

2. The combination, with a stationary disk and a rotating disk, each having inclined reducing-surfaces that form a diverging or funnel-like space between them, of throwing-edges *h*, secured to the rotating disk, the said edges operating to throw the grains endwise between the reducing-surfaces, and the latter to split them lengthwise, substantially as shown and described.

3. The combination, with a stationary re-

ducing-surface, of a rotating disk provided with a co-operating reducing-surface and ledges *h*, the outer ends of which terminate a considerable distance from the said reducing-surfaces, 5 and thus provide a free space for the flight of the material, substantially as shown and described.

4. The combination, with a stationary disk, *f*, provided with a reducing-surface and a ledge, 10 *t*, of a rotating disk, *b*, also provided with a reducing-surface, and having throwing-ledges *h*, substantially as shown and described.

5. The combination, with a stationary and a rotating disk, each provided with reducing- 15 surfaces, a feeding device communicating centrally with said disks, and a continuous delivery-channel receiving the reduced material from the periphery of said disks, of fans *p*, attached to the rotating disk and running in the 20 inner part of said delivery-channel, whereby a current of air is drawn through the feeding-channel, and, mingled with the material, passes through the reducing-surfaces and into the delivery-channel, thus acting as a carrier 25 for the material and operating to cool the same and the disks, substantially as shown and described.

6. The combination, with a stationary and a rotating disk, each provided with reducing- 30 surfaces, a feeding device communicating centrally with said disks, a delivering-channel receiving the reduced material from the peripheries of said disks, and openings 11, of fans *p'*, attached to the rotating disk and running 35 in the inner part of said delivering-channel, whereby a current of air is drawn through the openings 11 from behind said disks and mingles with the material that passes through the reducing-surfaces and into the delivering-channel, 40 thus acting as a carrier for the material and operating to cool the same and the disks, substantially as shown and described.

7. The combination, with the feed-channel *g* and conducting-channel *g*, of a rotating disk, *b*, provided with a reducing-surface and with 45 fan-blades *p*, arranged to draw air through the feed-channel *g*, and with fan-blades *p'*, drawing air from behind the said disk, both series of blades delivering the air, together with the grist, into said channel *g*, surrounding the 50 disk, substantially as and for the purpose described.

8. The means for attaching the rings *C* and *e*, that are provided with the reducing-surfaces, to the disks *b* and *f*, the same consisting, in the combination, with said rings and disks, of the rings *d* and *e*, overlapping said rings *C* *e*, and screwed onto offsets of the disks, 55 substantially as shown and described.

9. The combination, with a stationary disk, *f*, provided with a reducing-surface, of an adjusting-ring, *i*, working on screw-threads on the body of the said disk and abutting against the frame of the machine, with means for rotating the said ring and means for maintaining it pressed into position with any required degree of force, substantially as shown and described. 60

10. The combination, with a stationary disk, *f*, provided with a reducing-surface, of an adjusting-ring, *i*, working on screw-threads on the body of the said disk and abutting against the frame of the machine, with means for rotating the said ring to adjust the reducing-surfaces, substantially as shown and described. 70 75
